[57] CLAIM

The ornamental design for a filler for liquid containers,
as shown and described.

DESCRIPTION

FIG. 1 is a side elevational view of a filler for liquid containers showing my new design, the opposite side being a mirror image of the side shown;
FIG. 2 is a top plan view thereof;
FIG. 3 is a bottom plan view thereof;
FIG. 4 is an elevational view taken from one end thereof; and
FIG. 5 is an elevational view taken from the end opposite that shown in FIG. 4.
